(57) **CLAIM**

The ornamental design for a body of an industrial camera for machine vision, as shown and described.

DESCRIPTION

1. Body of an industrial camera for machine vision

1.1 is a front view of my design;

1.2 is a back view thereof;

1.3 is a top view thereof;

1.4 is a bottom view thereof;

1.5 is a left view thereof;

1.6 is a right view thereof; and

1.7 is a perspective view thereof.

The broken lines depict portions of the body of an industrial camera for machine vision which form no part of the claimed design.
